US0D1009980S

(12) **United States Design Patent** (10) **Patent No.:** **US D1,009,980 S**
(45) **Date of Patent:** **** Jan. 2, 2024**

(54) **SPECTACLES**

(71) Applicant: **CARTIER INTERNATIONAL AG**,
Steinhausen (CH)

(72) Inventors: **Nicola Bonaventura**, Treviso (IT);
Sara Furin, Valsauzibio (IT)

(73) Assignee: **CARTIER INTERNATIONAL AG**,
Steinhausen (CH)

(**) Term: **15 Years**

(21) Appl. No.: **29/722,404**

(22) Filed: **Jan. 29, 2020**

(30) **Foreign Application Priority Data**

Aug. 1, 2019 (WO) WIPO86092

(51) **LOC (14) Cl.** **16-06**

(52) **U.S. Cl.**

USPC **D16/335**

(57) **CLAIM**

The ornamental design for spectacles, as shown and described.

DESCRIPTION

FIG. 1 is a perspective view of spectacles, showing our new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof; and,

FIG. 7 is a bottom view thereof.

The broken lines are for the purpose of representing the environment and form no part of the claimed design.

1 Claim, 7 Drawing Sheets
